CLAIM

We claim the ornamental design for a thermostat, as shown and described.

DESCRIPTION

FIG. 1 is a front perspective view from above of a thermostat according to the claimed design;

FIG. 2 is a front side view of the claimed design of FIG. 1; FIG. 3 is a rear side view of the claimed design of FIG. 1; FIG. 4 is a right side view of the claimed design of FIG. 1; FIG. 5 is a left side view of the claimed design of FIG. 1; FIG. 6 is a top view of the claimed design of FIG. 1; and, FIG. 7 is a bottom view of the claimed design of FIG. 1. The broken lines in the drawings form no part of the claimed design.

1 Claim, 7 Drawing Sheets

Related U.S. Application Data

a continuation of application No. 29/608,761, filed on Jun. 26, 2017, now Pat. No. Des. 821,897, which is a division of application No. 29/548,334, filed on Dec. 11, 2015, now Pat. No. Des. 790,369.
